CLAIM

The ornamental design for a shoe outsole bottom, as shown and described.

DESCRIPTION

FIG. 1 is a perspective view of a first embodiment of a shoe outsole bottom in accordance with our new design.

FIG. 2 is a bottom plan view thereof;

FIG. 3 is a perspective view of a second embodiment of a shoe outsole bottom in accordance with our new design; and, FIG. 4 is a bottom plan view thereof.

The broken lines shown in the drawings represent the boundaries of the claim as well as portions of the shoe outsole bottom that form no part of the claimed design. The

(Continued)

broken lines, elements they depict, and broken line boundaries form no part of the claimed design.

1 Claim, 2 Drawing Sheets
